Pedersen, P.A.(57) **CLAIM**

The ornamental design for a conduit bender, as shown and described.

DESCRIPTION

FIG. 1 is a perspective view of a conduit bender showing my new design;

FIG. 2 is a left side elevation view thereof;

FIG. 3 is a right side elevation view thereof;

FIG. 4 is a front elevation view thereof;

FIG. 5 is a top plan view thereof; and,

FIG. 6 is a perspective view thereof when coupled to a bender shoe and a remote user interface.

The broken lines in the drawings illustrate portions of the conduit bender and environmental structure of a bender shoe with remote user interface that form no part of the claimed design.
